UNITED STATES PATENT OFFICE.

LEO ROSEMAN, OF NEWARK, NEW JERSEY.

GARMENT-FASTENER MEANS.

Application filed April 13, 1927. Serial No. 183,297.

This invention relates, generally, to improvements in fastener means for garments; and more especially to novel constructions of fastener elements adapted for cooperation 5 with hook-fasteners such as are commonly employed in connection with women's garments.

The present invention has reference to an improved species of female or hook engageable fastener means of the generic type disclosed in my copending applications for United States Letters Patent Serial Number 119,851, filed July 1st, 1926, and Serial Number 156,474, filed December 22nd, 1926, 15 wherein the basic structure comprises a pocket-forming strip or member suitably applied along a body forming either an attached or an integral part of a garment opening edge so as to provide hook-bill receiving pockets entering under the inwardly directed edge of said strip or member and extending beneath the same.

The present invention has for its principal object to provide in connection with each 25 hook-bill receiving pocket a metallic fastener element having a portion exposed at the mouth of each said pocket so as to be both visible to the eye, whereby the location of the pockets are more easily discernible, and 30 whereby, at the same time, the mouths of the pockets are provided with metallic fastener elements or lips directly engageable by the hook fastener in a metal to metal contact. To this end the pocket forming strip 35 is provided with an edge having cutaway portions or notches across which extend and through which are exposed the lip-bars of metallic fastener elements which both define and reenforce the hook-bill receiving pockets; a novel arrangement and combination 40 of sewn stitches being employed to both anchor the metallic fasteners in place and at the same time connect the pocket forming strip to the base material so as to form the 45 desired hook-bill receiving pockets.

Other objects of the present invention, not at this time more particularly enumerated, will be clearly understood from the following detailed description of the same.

50 The invention is clearly illustrated in the accompanying drawings, in which:—

Figure 1 shows the novel garment fastener means of this invention in the form of a fastener tape, the said tape being shown in 55 face view, a portion of a garment body be-

ing also shown in operative attached relation thereto; Figure 2 is an edge view of the garment fastener means, looking in the direction of the arrow 2 in Figure 1; and Figure 3 is a transverse section taken on 60 line 3—3 in Figure 1, said view being drawn on a greatly enlarged scale.

Figure 4 is a face view of the fastener tape, illustrating the initial steps of the preferred method of applying and initially 65 securing the metallic fastener elements in the notched folded edge of the pocket-forming strip portion of the tape.

Figure 5 is a detail face view of the fastener tape, illustrating a slightly modified 70 form of initial stitching for applying and securing the metallic fastener elements in the notched folded edge of the pocket forming strip portion.

Figure 6 illustrates a modified form of 75 the novel fastener means in face view, in which the pocket forming strip is of single ply form sewn to the tape or other body, and having cutaway portions in its inner edge with which the metallic fastener elements are operatively associated; and Figure 7 is a transverse section of the same, 80 taken on line 7—7 in Figure 6 but drawn on an enlarged scale.

Similar characters of reference are employed in all of the hereinabove described views, to indicate corresponding parts.

Referring to Figures 1 to 4 inclusive of the drawings, the novel fastener means is shown therein in the preferable form of a 90 tape provided with a pocket-forming strip section having pocket defining and reenforcing metallic fastener elements arranged and combined therewith in accordance with the principles of this invention. It will be obvious, however, that the pocket-forming strip section may be formed from and integrally made the marginal edge portion of a garment body where so desired. The reference character 6 indicates the body of the 95 tape, having its rearward longitudinal marginal portion 7 folded over and forwardly upon its body. The forward longitudinal marginal portion of the tape is utilized to provide a pocket-forming strip or section 100 8, which in such case forms an integral portion of the tape body. It will be understood, however, that should it be so desired, the pocket-forming strip may be provided 105 as a separate member disposed upon and se- 110

cured to the face of the tape body or directly to a garment edge portion, without departing from the principles of construction hereafter more fully set forth. In 5 making up the novel fastener means in the form shown in Figures 1 to 4 inclusive, the pocket-forming strip or section 8 is first folded lengthwise upon itself, thus providing an inturned section 9 forming an intermediate folded edge 10. This folded edge is cut away at longitudinally spaced intervals, corresponding to the desired spacing of the hook-bill receiving pockets to be provided, to form notches or marginal openings 15 11. Disposed so as to lie intermediate the strip or section 8 and its inturned section 9, which together provide the pocket forming strip, are pocket defining and reenforcing fastener elements having portions extending 20 across and exposed through the notches or marginal openings 11. Said elements may be made of any suitable material to provide pocket-lip forming bars or members extending longitudinally within and 25 through the folded edge 10 so as to be exposed by the notches or marginal openings 11 at the mouth of each hook-bill receiving pocket; said bars having at each end suitably formed abutments cooperating with 30 pocket forming stitching subsequently described, to retain said bars against displacement.

In the preferred form thereof, said pocket defining and reenforcing fastener 35 elements are made of metallic wire rectangularly shaped to provide a front or lip bar 12, from the opposite ends of which extend abutment forming side bars 13 terminating in a back bar 14 inwardly spaced 40 from but parallel to said lip bar 12. It will be understood that this formation of fastener element need not necessarily be made of metallic wire, since it may be provided in the form of a stamping of metal, fibre or any 45 other substantially rigid material found desirable; and it will also be understood that the shape thereof may be varied if desired, the provision of the lip bar being the essential feature. After inserting the fastener 50 elements within said folded edge 10 and before applying the pocket-forming strip upon the body to which it is to be attached, as e. g. before turning the pocket-forming strip inwardly and over upon the tape body 55 6-7, it is preferable to stitch together the sections 8 and 9 of the strip so as to also initially secure the fastener elements in place. To this end the pocket-forming strip or section is submitted to a sewing machine 60 operation whereby a primary line of running stitches 15 are sewn through the section 8 and section 9, so as to traverse the side bars 13 of the fastener elements, and at the same time by stitches 15' extending 65 between the side bars 13 of each fastener

element, securing together and binding the inner margins of the notches or openings 11. In addition to said running stitches 15 and 15' groups of transverse bar stitches 16 are formed to traverse the back bar 14 of each 70 fastener element adjacent to the abutment forming side bars 13, such bar stitches serving to anchor the fastener elements against lateral displacement, and also, by reason of their adjacency to said abutment forming 75 side bars 13, serving to retain said fastener elements against longitudinal displacement. The said stitching, comprised in the stitches 15, 15' and 16, since it extends only through the folded sections 8 and 9 providing the 80 pocket-forming strip, does not in any way obstruct the pocket space formed beneath the latter when the same is applied to and upon a tape or garment body, as the case 85 may be.

Upon completion of the primary stitching 15, 15' and 16, the pocket-forming strip or section is turned and folded over upon the body to which it is to be applied, as e. g. the tape body 6-7, whereupon a second line of 90 stitching is sewn through the applied strip or section and the body to assemble and secure said parts in operative relation and so as to provide a series of longitudinally spaced hook-bill receiving pockets 17 opening along the free edge of and extending beneath the pocket-forming strip, the spacing 95 of which corresponds to the spacing of hook-fasteners to be separably coupled therewith. The said pockets 17 are formed by sewing down the free edge of the pocket-forming strip to the tape or other body by a line of 100 running stitches 18 which traverse the abutment forming side bars 13 of the fastener elements, but which are interrupted adjacent 105 to the inner sides of said side-bars 13, at which points are formed groups of outwardly extending transverse bar stitches 19, which traverse the fold edge 10 and the lip-bar 12 adjacent to each side of the notches or 110 openings 11, thereby both defining and reenforcing the sides of the formed hook-bill receiving pocket, and further aiding in retaining the fastener elements in proper position. Intermediate each group of side 115 bounding pocket defining bar stitches 19, and rearwardly offset beyond the mouth of the formed pockets are connecting stitching 18', which may be in the form of a series of 120 stitches or in the form of a single jump stitch as already fully described in my aforesaid co-pending applications.

Referring to Figure 5 I have shown there- 125 in a slight modification in the form and ar- rangement of the primary stitching which secures together the sections 8 and 9 of the pocket-forming strip, and which traverses the fastener elements. This modified ar- rangement of primary stitching comprises a line of running stitches 20 which trav- 130

erses the side bars 13 of the fastener elements, but which includes intermediate the opposite side-bars of each fastener element zig-zag stitching 20', which securely sews together the inner margins of the notches or openings 11.

Referring now to Figures 6 and 7, I have shown a modified form of simplified fastener means, the same comprising a base, 10 such as the tape body 6, upon which is applied a pocket forming strip 21 consisting of a tape or strip of material in the inner edge portion of which are provided the notches or openings 22. Disposed intermediate the body 6 and pocket forming strip 21 are the fastener elements having the lip bar 23 and side bars 24, the same being arranged so that the former extends across the notch or opening 22. The inner edge of 20 the strip 21 is secured to the body 6 by a line of running stitches 25 which is interrupted adjacent to each side of the notch or opening 22, at which points bar stitches 26 are formed to traverse the lip-bars 23 adjacent 25 to the side bars 24, thus holding the fastener elements against displacement and at the same time forming or defining the sides of the hook-bill receiving pockets with which the fastener elements are associated. Additional bar stitches 26' are provided to extend outwardly over the edge of the strip 21 at each side of the notch or opening, thereby further reenforcing the pocket construction; and intermediate the groups of bar- 30 stitches 26' are the off-set running or jump stitches 25'. The outer edge of the strip 21, in this type of construction as shown, is sewn to the body 6 by stitching 27; it will be understood, however, that the strip 21 may 35 be made integral with the body 6 and folded over thereupon if so desired.

It will be apparent that, in the broader aspects of the instant invention, various means, other than the specific form of stitching above described, may be resorted to for securing the pocket-forming strip and its fastener elements to the body upon which it is to be applied, while nevertheless obtaining a fastener means essentially within the scope 50 of the present invention, hence I do not desire to limit myself entirely to the specific form of fastening stitches herein described and shown.

From the above description of the instant 55 invention, and from an inspection of the accompanying drawings, it will be clearly evident that I have provided an improved form of female fastener means in the form of hook-bill receiving pockets, which are 60 bounded along their entrance mouths with a visible metallic lip-bar calculated to render the pocket location more easily discernible to the user, and at the same time providing for a metal to metal contact of hook-fasteners therewith which will avoid wear upon or

fraying of fabric material, and which will consequently provide a fastener means of the pocket type adapted to retain a good appearance during the service life of the same.

Having thus described my present invention, I claim:

1. A garment fastener means separably engageable by hook-fasteners, comprising a pocket-forming strip having a longitudinally folded inner edge provided with openings indenting the fold thereof at the location of each pocket, rigid pocket defining and reenforcing members within the folded edge of said strip having exposed lip-forming portions extending across said openings 80 at the mouth of each pocket, means upon which said pocket-forming strip is applied, and means for securing said strip and its members, in pocket-forming relation to said latter means.

2. A garment fastener means separably engageable by hook-fasteners, comprising a pocket-forming strip having a longitudinally folded inner edge provided with openings indenting the fold thereof at the location of each pocket, rigid pocket defining and reenforcing members within the folded edge of said strip having exposed lip-forming portions extending across said openings 90 at the mouth of each pocket, means upon which said pocket-forming strip is applied, and means for securing said strip and its members, in pocket-forming relation to said latter means.

3. A garment fastener means separably engageable by hook-fasteners, comprising a pocket forming strip having a longitudinally folded inner edge provided with openings indenting the fold thereof at the location of each pocket, metallic fastener members within the folded edge of said strip having exposed lip-forming portions extending across said opening at the mouth of each pocket, stitching joining together the folds of said strip and traversing said fastener members, a portion of said stitching being disposed close to the inner ends of said indented openings, means upon which said pocket-forming strip is applied, additional stitching to secure said folded edge of said strip to said means upon which the same is applied, and said latter stitching traversing portions of said fastener members but being interrupted at intervals to form hook-bill receiving pockets entering under the lip-forming portions of said members.

4. A garment fastener means separably engageable by hook-fasteners, comprising a pocket forming strip having a longitudinally folded inner edge provided with openings indenting the fold thereof at the loca- 130

tion of each pocket, metallic fastener members within the folded edge of said strip having exposed lip-forming portions extending across said openings at the mouth of each pocket, stitching joining together the folds of said strip, and traversing the sides of said fastener members, said stitching including groups of transverse bar-stitches traversing inner portions of said fastener members, said stitching further including binding stitches bordering the inner ends of said indented openings, means upon which said pocket-forming strip is applied, additional stitching to secure said folded edge of said strip to said means upon which the same is applied, and said latter stitching traversing portions of said fastener members but being interrupted at intervals to form hook-bill receiving pockets entering under the lip-forming portions of said members.

5. A garment fastener means separably engageable by hook-fasteners, comprising a base, a pocket-forming strip on said base having a longitudinally folded inner edge provided with openings indenting the fold thereof at the location of each pocket, metallic fastener members within the folded edge of said strip having exposed lip-forming bars extending across said openings at the mouth of each pocket and side bars extending inwardly from the ends of said lip-forming bars, stitching to secure said folded edge to said base, said stitching traversing said side bars and including transverse bar stitches extending outwardly over said folded edge and the enclosed portions of said lip-forming bars adjacent to each side of said indented openings, and said stitching also including stitching between said groups of transverse bar stitches off-set on said base beyond the mouth of each pocket.

6. A garment fastener means separably engageable by hook-fasteners, comprising a base, a pocket-forming strip on said base having a longitudinally folded inner edge provided with openings indenting the fold thereof at the location of each pocket, metallic fastener members within the folded edge of said strip having exposed lip-forming bars extending across said openings at the mouth of each pocket and side bars extending inwardly from the ends of said lip-forming bars, stitching joining together the folds of said strip and traversing the side bars of said fastener members, and additional stitch-

ing to secure said folded edge of said strip to said base, said latter stitching traversing said side bars of said fastener members and including transverse bar stitches extending outwardly over said folded edge and the enclosed portions of said lip-forming bars adjacent to each side of said indented openings, and said stitching also including stitching between said groups of transverse bar stitches off-set on said base beyond the mouth of each pocket.

7. A garment fastener means separably engageable by hook-fasteners, comprising a base, a pocket-forming strip on said base having a longitudinally folded inner edge provided with openings indenting the fold thereof at the location of each pocket, metallic fastener members within the folded edge of said strip having exposed lip-forming bars extending across said openings at the mouth of such pocket and side bars extending inwardly from the ends of said lip-forming bars, stitching joining together the folds of said strip and traversing the side bars of said fastener members, said stitching including transverse bar stitches adjacent to said side bars and further including binding stitches bordering the inner ends of said indented openings, and additional stitching to secure said folded edge of said strip to said base, said latter stitching traversing said side bars of said fastener members and including transverse bar stitches extending outwardly over said folded edge and the enclosed portions of said lip-forming bars adjacent to each side of said indented openings, and said stitching also including stitching between said latter bar stitches off-set on said base beyond the mouth of each pocket.

8. A garment fastener means separably engageable by hook-fasteners, comprising a main body, a pocket-forming strip overlying said main body, rigid pocket reinforcing members underlying said strip and having exposed portions bounding and defining the mouths of said pockets, stitching to secure said body, strip and reinforcing members in assembled relation, and said stitching including groups of transverse bar stitches to traverse and anchor said reinforcing members against displacement.

In testimony, that I claim the invention set forth above I have hereunto set my hand this 8th day of April, 1927.

LEO ROSEMAN.
